UNITED STATES PATENT OFFICE.

PHILIP HÄCKLER, OF MINNEAPOLIS, MINNESOTA.

LUBRICATOR.

SPECIFICATION forming part of Letters Patent No. 337,396, dated March 9, 1886.

Application filed July 22, 1885. Serial No. 172,337. (No model.)

To all whom it may concern:

Be it known that I, PHILIP HÄCKLER, a citizen of the United States, and a resident of Minneapolis, in the county of Hennepin and State of Minnesota, have invented certain Improvements in Lubricators, of which the following is a specification.

My invention relates particularly to improvements in lubricators designed for use with the lower roll or shaft of a grain-elevator. These rolls are located at the lower end of an elevator-leg, in what is known as the "elevator-boot," and in a position that is not easily accessible, so that it is inconvenient to use any of the common forms of lubricators for lubricating this shaft.

My invention consists in the construction and combination of devices hereinafter described, and particularly pointed out in the claim.

In the drawings forming part of this specification, Figure 1 is a side elevation of an elevator-leg having my improved lubricator applied thereto. Fig. 2 is a vertical cross-section of the shaft and lubricator.

In the drawings, H, Fig. 1, represents the frame of an elevator-leg. I is the belt, and J the boot. The shaft A is the lower shaft or roll of the elevator, and it is located in the boot J. The shaft A is journaled in the box B. The upper box, B, is provided with an inclined hole through it radial with the shaft A. Into this hole is fitted a pipe, C. This pipe is of east-iron, usually a piece of three-quarter-inch gas-pipe about twenty-six inches long. The upper end of the pipe is screw-threaded at c, and a threaded cap, D, is fitted thereon. This cap is provided with the small hole d, extending through it.

Within the pipe C, and bearing on the shaft A, is the cylinder or roll of grease G. This roll is preferably composed of the following ingredients in substantially the proportions specified: beeswax, three-quarters of a pound; paraffine, one pound; graphite, three ounces; castor-oil, one pint; and in cold weather I

prefer to add crude oil, one pint. This compound is made into a roll or cylinder that is a little less in diameter than the inside of the pipe, so that it moves freely therein. 50

E is a plunger or follower, of metal, that has an eye, e, into which the wire F is secured by an eye, f'. The wire F extends through the hole d in the cap D, and is provided at its upper end with the ring f. The wire F and the follower E are together about two inches shorter than the pipe C, so that when the ring f strikes on the cap D the lower end of the follower is at about that distance from the shaft. It is therefore impossible for the follower at any time to come in contact with the shaft. When the ring comes in contact with the cap, it will indicate to the workman or operative that the grease is nearly all exhausted, and that a new supply is required; 65 but should this be neglected the contact of the ring with the cap will keep the follower from coming in contact with and wearing the shaft. When used in other locations, the pipe may be in an upright position. In either case the 7c weight of the metal plunger prevents the pushing of the grease up in the pipe, and when the pipe is inclined this result is secured while a part of the weight of the plunger is borne by the wall of the pipe. 75

I claim as my invention—

The combination of the elevator-boot J, shaft A in the lower part thereof, box B, surrounding said shaft, and formed with an inclined hole through it radial to shaft A, the 80 inclined pipe C, having its lower end fitted in the inclined hole of the box, the follower E, fitting in said pipe, and having eye e, the wire F, having ring f', engaging with eye e, the cap D, and the roll of grease G, all substantially as described. 85

PHILIP ^{his} X HÄCKLER.
mark.

In presence of—

AMASA C. PAUL,
JOHN PLUGRADT.
